UNITED STATES PATENT OFFICE.

SAMUEL A. HOLMES, OF STORM LAKE, IOWA.

CRUTCH CHAIR.

Application filed April 11, 1922. Serial No. 551,491.

To all whom it may concern:

Be it known that I, SAMUEL A. HOLMES, a citizen of the United States, residing at Storm Lake, in the county of Buena Vista 5 and State of Iowa, have invented a new and useful Crutch Chair, of which the following is a specification.

This invention relates to a combined crutch and stool, the primary object of the invention being to provide novel means, whereby 10 the lower portion of a crutch may be converted into a stool.

Another object of the invention is to provide a foldable seat section so constructed 15 that it may be folded to a position between the side bars of the crutch when the seat is not in use.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed, may be made within the scope of what is claimed, without departing from the spirit of the invention.

Referring to the drawing:

30 Figure 1 is a side elevational view of a crutch constructed in accordance with the present invention.

Figure 2 is an elevational view showing the cover forming a part of the invention, 35 as in its open position.

Figure 3 is an elevational view disclosing the lower portion of the crutch as extended to provide a stool or seat.

Figure 4 is a detail view disclosing the 40 connection between the stool frame and bars of the crutch.

Figure 5 is a fragmental detail view disclosing the brace employed for holding the bars of the crutch in spaced relation.

45 Figure 6 is an elevational view of the crutch showing the seat portion in its active position.

Figure 7 is a detail view of the removable seat portion of the stool.

50 Referring to the drawings in detail, the crutch embodies side bars 5, each of which includes an upper section 6 and a lower section 7. A hinge 8 is connected to each of the sections of the respective side bars for 55 pivotally connecting the section.

Braces 9 are provided on each of the side

bars 5 at points adjacent to the hinges 8, which braces are formed with elongated openings to accommodate bolts 10 that secure the braces to the sections, whereby 60 movement of the braces will be permitted, when the sections 7 are moved outwardly in the formation of the stool. These braces restrict movement of the lower section 7 to prevent them from moving too far, when 65 the sections are spread apart as shown by Figure 3 of the drawings.

Secured to the sections 7 is a brace 11 that is pivoted intermediate its ends as clearly shown by Figure 5 of the drawings, for 70 holding the sections 7 in their extended positions when the stool portion is unfolded. The stool includes pivoted side members 12 each of which being provided with an elongated opening 15 adapted to receive the 75 screw 14 that is secured to the side bar or section 7, associated therewith, the elongated openings permitting movement of the side members 12, with respect to the sections 7. The forward portions of the side members 80 12 are pivotally connected as by means of the bolt 15 so that the seat portion is substantially triangular in formation. Disposed between the outer ends of the side members 12 are the pivoted legs 16 which 85 provide the forward support for the seat section, a chain 17 being provided for holding the legs against movement away from each other.

Brace bars 18 are pivotally connected with 90 the side members 12 as at 19, and are formed with notches 19' to be fitted over the screws 20, carried by the sections 7 of the side members, so that the brace bars may be secured to prevent movement of the lower 95 section, with respect to the seat portion of the stool. A seat cover forms a part of the invention and embodies a pair of rods 21 that are pivotally connected as at 22, the cover proper which is indicated at 23 being 100 made of leather or similar flexible material and formed with pockets adjacent to the side edges thereof, for the reception of the rods 21.

The free ends of the rods are adapted to 105 be positioned through the eye bolts 24 that are supported on the sections 7 adjacent to the upper ends thereof.

From the foregoing it will be seen that I have provided a crutch structure wherein 110 the lower section thereof may be moved to form a stool or chair, the entire structure

- being exceptionally light to lend comparatively slight extra weight to the crutch proper. In order that the lower ends of the sections 7 may be held against movement, 5 a ring member 25 is provided, and slipped over the ends of the lower sections, suitable cushioning means being secured to the ring member to cushion the jar caused by the crutch contacting with the ground surface.
- 10 A flexible covering indicated at 26 is secured to one of the sections 7, the remaining portion thereof being of a construction to fit around the sections 7 when the stool portion has been folded to a position between 15 the sections 7, thereby housing the stool structure. Suitable snapbuttons 27 are provided for holding the flexible covering in position.
- Having thus described the invention, what 20 is claimed as new is:—
1. A crutch comprising side bars, each of 25 said side bars including an upper section and a lower section, the sections of each side bar being hingedly connected, means for bracing the sections of the side bars with respect to each other, and a foldable stool section supported between the lower sections.
2. A crutch comprising side bars, each of 30 said side bars including an upper section and a lower section hingedly connected, side members pivotally supported between the sections, said side members forming the upper portion of a stool, hinged members for 35 bracing the side members, pivoted leg mem-

bers having connection with the side members, said side members and leg members adapted to fold to a position between the lower sections, and a removable seat cover adapted to be fitted on the side members. 40

3. A crutch comprising side bars, each of said side bars including upper and lower sections, means for hingedly connecting the upper and lower sections, a stool including side members having pivotal connection with 45 the side bars, said side members adapted to fold between the side bars, pivoted leg members having connection with the side bars, means for bracing the side bars, and means for holding the lower sections together at 50 the lower ends thereof.

4. A crutch comprising side bars, each of said side bars including an upper section and a lower section, means for pivotally connecting the sections, means for restricting movement of the sections with respect to each other, a seat portion including side members pivotally connected with the lower sections, leg members for supporting the side members, a removable seat cover, and means embracing the lower ends of the lower sections for securing the lower sections together. 55

In testimony that I claim the foregoing as my own, I have hereto affixed my signature in the presence of two witnesses. 60

SAMUEL A. HOLMES.
